UNITED STATES PATENT OFFICE.

FRANK E. MODLIN, OF ST. JOSEPH, MISSOURI.

GAS PRODUCER.

Application filed June 1, 1922. Serial No. 565,258.

To all whom it may concern:

Be it known that I, FRANK E. MODLIN, a citizen of the United States, residing at St. Joseph, in the county of Buchanan and State of Missouri, have invented certain new and useful Improvements in Gas Producers, of which the following is a specification.

My invention relates to improvements in gas producers and its main object is to provide a retort or machine of this class that is of simple construction and neat appearance, very compact and has such small dimensions that it may be used, not only as a stationary plant, but also used conveniently on a tractor for supplying motive force to its engine.

Another object resides in the fact that the machine delivers the resulting gas in a pure and highly refined condition having had all tar, oil, or other impurities washed away during the process of generation.

Another object is to provide a gas producer, that utilizes an inferior quality of coal, such as bituminous or lignite coal and produces a first class gas.

In the accompanying drawings one embodiment of the invention is illustrated, and—

Figure 1 shows a vertical section of the gas producer;

Fig. 2 is a top plan view thereof;

Fig. 3 is a horizontal section along line 3—3 of Fig. 1;

Fig. 4 is a horizontal section in larger scale along line 4—4 of Fig. 1, and

Fig. 5 is a vertical section along line 5—5 of Fig. 2.

This gas producer consists of a furnace 10 with an inclined grate 11 at the bottom, supported on an angle bar 12 secured at the rear of the furnace and on a transverse rail 13 secured near the front thereof in the base 14. This rail 13 is spaced slightly back of the front wall 15 of the base and connected therewith by means of a number of short grate bars 16 and above this rail is a door 17 for removing clinkers. The base 14 contains an ash pit 18 to which leads an opening 19 closed by a door 20 provided with adjustable draft apertures 21 for regulating the draft in the furnace.

The furnace is surrounded on three sides by a water jacket formed by double walls 22 at the rear of the furnace and double walls 23 at each end thereof. The jacket formed on these three sides of the furnace is filled with water through a cock 24 provided near

the upper end thereof so as to produce a water line indicated by "W" in Fig. 1 approximately three-fourths of the height from the bottom of the jacket. The heat in the furnace will cause this water to evaporate and the steam formed above the water line may be drawn off through a pipe 25 opening below the grate 11 into the ash pit, as at 26, and a cock 27 is provided on this pipe 25 for communicating with the steam chamber at the top of the jacket.

The entire front and a part of the top of the furnace, which is slanting rearwardly as at 28, is covered by a tank 29 containing water and forming a filtering chamber for the gas. As best seen in Fig. 1 the furnace, together with the water jacket 22 and the tank 29, is secured in the base 14 by means of securing bolts 30 to form a rigid construction.

The upper part of the tank is provided with a grating or sieve 31 and upon this sieve is deposited a scrubbing material, such as excelsior or wood shavings 32. The scrubbing material is held in position by means of a screen 33 to prevent it from being drawn out through the delivery pipe 34 for the gas. This pipe is secured in the lid 35 which is held down over the upper part of the tank, as at 36, by means of bolts or rivets. As will be seen in Fig. 1 the sieve or grating 31 is placed slightly below the top plate 37 of the furnace. This is done for the purpose of delivering heat to the scrubbing material through the wall 28 of the furnace and to heat the compartment in which the scrubbing material 32 is deposited.

In the top plate 37 is provided an opening 38 above which is secured a dome 39 adapted to collect the gases produced in the furnace. From this dome 39 a large tube 40 runs downwardly to the lower end of the tank 29 where it opens into a transverse pipe 41 secured in the tank. The opposite end of the pipe is closed, but its upper side is provided with perforations 42 for the gas coming down from the furnace into the latter. In order to compel the gas to take this course an exhaust 43, preferably consisting of a vacuum pump, is inserted in the tube 40 and this pump may be driven in any suitable manner, as by a belt 44 actuated by an engine.

Water is supplied to the tank 29 through a pipe 45 opening at the bottom of the tank

and the flow of water is regulated in any suitable manner so that the water line, as at "L", is formed a short distance below the sieve 31. An exhaust pipe 46 situated with its axis in the water line is intended to remove all impurities floating on the water. This pipe 46 leads into a seal box 47 of usual construction so as to prevent the gas from escaping from the same.

10 The fuel is delivered to the furnace from a hopper 67 above the top of the furnace. This hopper opens into a feed box 48 preferably of circular formation and constructed with a rotating drum 50 mounted on a spindle 49 in the center of the box. This spindle may be rotated by hand or by a governor on the engine for automatically feeding coal into the furnace. The rotating drum 50 has four radial arms 51 connected by a cylindrical outer wall 52 and preferably positioned at right angles to each other to form between them four sector-shaped compartments of equal size. In this manner four sections are provided which are open at top and bottom. The drum rests on a bottom plate 53 of the box 48 which is rigidly supported in any suitable manner at the top of the furnace. The roof or top plate 54 of the box has a central boss 55 for the spindle 49 and is held down on spacing columns 56 by means of nuts and stud bolts 57 tapped into the upper ends of the columns and between the nuts and the roof plate 54 are inserted compression springs 58 for pressing the roof plate against the drum 50. In this manner the roof plate 54 is held in position without giving undue pressure against the drum and this pressure can be regulated by means of the nuts 57. The roof plate 40 54 has a sector shaped aperture 59 at one side of the spindle. This aperture is of the same size as each compartment formed in the drum between the arms 51. The bottom plate 53 has a corresponding aperture 45 60 of the same size and is situated on the opposite side of the spindle 49 and opens into a chute 61 entering through the jacket 22 to deliver coal into the furnace. This chute 61 is preferably widened at its lower end, as seen at 62, in Fig. 2, to facilitate the dropping out of the coal.

50 The inclination of the grate 11 is approximately 30° and in this manner a coal bed will be provided in the furnace of substantially uniform thickness above the grate, as seen in Fig. 1.

55 The gas producer is used in the following manner: The jacket 22 is filled with water until a level is reached, as indicated by "W" in Fig. 1. Similarly the tank 29 is filled until the water reaches a little below the level marked "L". It should here be noted that the tank 29 is entirely independent of the water jacket and that there is 60 no communication between the two. In case

the furnace is entirely empty the filling is now accomplished in the following manner. The hopper 67 receives coal from the coal bin either by hand or by automatic delivery and if the compartment in the drum beneath the hopper is empty it will be immediately filled from the hopper while the other three pockets remain empty. By revolving the drum a quarter turn the filled compartment will leave the hopper and the drum will 70 present another empty compartment beneath the hopper which is in turn filled. By again turning the drum the same amount, the first filled compartment will then register with the chute 61 and deliver its contents into the same; while the second compartment will be closed by the top and bottom plates of the box 48; and the third empty compartment presented under the hopper 67. As soon as this third compartment is filled the 75 drum is again revolved and the first filled compartment will be turned away empty from the chute and the second compartment deliver its contents into the chute while the drum presents the fourth empty compartment under the hopper 67. This operation is repeated until a sufficiently high coal bed is produced in the furnace which is now lit and the draft regulated by means of the ash door 20.

80 When sufficient heat is produced in the furnace, gas forms in the upper part thereof and enters into the dome 39. At the same time the water jacket 22 and the tank 29 will be heated and steam produced in both. The steam from the water jacket may now be permitted to run into the ash pit through the pipe 25 to facilitate disintegration of the coal and production of gas. As soon as the water in the tank 29 is sufficiently hot and a quantity of gas has been 85 formed in the furnace, the pump 43 is started to draw off the gas from the dome 39 and conduct it into the perforated tube 41 to deliver the same at the bottom of the tank. This gas will now percolate through the hot water in the tank 29 and rise to the 90 surface therein, while the impurities, such as oil and tar, will be removed from the gas by the hot water and float on top of the water to be taken out from the tank by the pipe 46 for further use. At the same time the purified gas will rise through the sieve 31 and pass through the scrubbing material 32 for drying and ultimately collect into 95 the delivery pipe 34. From there it might be conducted into a reservoir or led directly to an engine for immediate consumption.

100 On account of the suction created by the pump 43 all of the gas collected at the top of the furnace will be drawn into the dome 39 and the tube 40 but none of it will rise through the hopper 61 into the box 48. Should, however, a small part of the gas 105 happen to enter into the box 48 before the 110

5 pump has been started, this gas cannot escape to the atmosphere as the box is always sealed by means of the drum as there is no direct connection between the chute and the bottom opening 60 with the top opening 59 at any time or with any position of the drum, nor can atmospheric air enter through the seal. As already mentioned the drum 10 may be revolved by hand and the use of an ordinary wrench attached to the spindle 49; or by means of an engine and a governor, thereby making the delivery of coal automatic.

15 The water in the tank 29 is sufficiently heated to dissolve all impurities in the gas entering the bottom of the tank as the latter receives heat directly from the furnace through the front wall and inclined upper wall 28 thereof. The scrubbing material 32 20 is also sufficiently heated from the furnace so that the gas passing through the same is completely dried.

Having thus described the invention, what is claimed as new is:

25 1. In a gas producer having a furnace; a gas filtering tank covering one side and a portion of the top of said furnace and containing water, a water filled jacket enclosing the other sides of the furnace, and

30 means including a perforated pipe near the bottom of said tank for delivering gas from the furnace into said filtering tank, said gas filtering tank being adapted to be heated by the furnace.

35 2. In a gas producer having a furnace; a gas filtering tank covering one side and a portion of the top of said furnace and the intervening walls being common for the furnace and the tank, the latter containing

40 water, a water filled jacket enclosing the other sides of the furnace, means including a perforated pipe in the tank for delivering gas from the furnace into said filtering tank, said gas filtering tank being adapted to be

45 heated by the furnace, said tank being partly funnel-shaped and provided with a sieve at its enlarged upper end, and a screen spaced above said sieve forming a scrubbing compartment above said sieve and a filtering 50 chamber below the same.

55 3. In a gas producer having a furnace; a gas filtering tank covering one side and a portion of the top of said furnace and containing water, a water filled jacket enclosing the other sides of the furnace, means for delivering gas from the furnace into said filtering tank, said means including a gas dome on the furnace, a perforated pipe in said tank adjacent the bottom thereof, and

60 a tube between said dome and said pipe.

65 4. In a gas producer having a furnace; a gas filtering tank covering one side and a portion of the top of said furnace and containing water, a water filled jacket enclosing the other sides of the furnace, means

for delivering gas from the furnace into said filtering tank, said means including a gas dome on the furnace, a perforated pipe in said tank adjacent the bottom thereof, a tube between said dome and said pipe, and 70 an exhauster in said tube.

5. In a gas producer having a furnace; a gas filtering tank covering one side and a portion of the top of said furnace and containing water, a water filled jacket enclosing the other sides of the furnace, means for delivering gas from the furnace into said filtering tank, said gas filtering tank being adapted to be heated by the furnace, 75

said tank being funnel-shaped and provided with a sieve at its enlarged upper end, a screen spaced above said sieve forming a scrubbing compartment above said sieve and a filtering chamber below the same, said compartment being filled with scrubbing

80 material such as wood shavings, said chamber being filled with a liquid forming the filtering material, a conduit above said screen adapted to collect the purified gas,

85 said means including a gas dome on the furnace, a perforated pipe in said tank adjacent the bottom thereof, a tube between said dome and said pipe, and an exhauster in said tube.

6. In a gas producer having a furnace; a gas filtering tank covering one side and a portion of the top of said furnace and containing water, a water filled jacket enclosing the other sides of the furnace, means including a perforated pipe in said tank for

90 delivering gas from the furnace into said filtering tank, a charging device for the furnace situated above and to one side thereof including a revoluble drum having a plurality of pockets open at top and bottom,

100 stationary top and bottom cover plates for said pockets, said cover plates each being provided with an aperture situated diametrically opposite each other and adapted to register with one of said pockets respectively,

105 and a chute widening downwardly and leading into said furnace and connecting with said aperture in the bottom cover plate, whereby upon one of said pockets being filled through said aperture in the top cover

110 plate, another pocket will deliver fuel into said chute for the furnace.

7. In a gas producer having a furnace; a gas filtering tank covering one side and a portion of the top of said furnace and containing water, a water filled jacket enclosing the other sides of the furnace, means for delivering gas from the furnace into said filtering tank, a charging device for the furnace including a revoluble drum having a plurality of pockets open at top and bottom,

120 stationary top and bottom cover plates for said pockets, said cover plates each being provided with an aperture situated diametrically opposite each other and adapted to

125 130

register with one of said pockets respectively, a chute leading into said furnace and connecting with said aperture in the bottom cover plate, whereby upon one of said pockets being filled through said aperture in the top cover plate, another pocket will deliver fuel into said chute for the furnace, means for delivering gas from the furnace into said filtering tank, said gas filtering tank 10 being adapted to be heated by the furnace, said tank being funnel-shaped and provided with a sieve at its enlarged upper end, and a screen spaced above said sieve forming a scrubbing compartment above said sieve and 15 a filtering chamber below the same, said compartment being filled with scrubbing material such as wood shavings and said chamber being filled with a liquid forming the filtering material.

20 8. In a gas producer having a furnace; a gas filtering tank covering one side and a portion of the top of said furnace and containing water, a water filled jacket enclosing the other sides of the furnace, means for delivering gas from the furnace into said filtering tank, a charging device for the furnace including a revoluble drum having a plurality of pockets open at top and bot-

tom, stationary top and bottom cover plates for said pockets, said cover plates each being 30 provided with an aperture situated diametrically opposite each other and adapted to register with one of said pockets respectively, a chute leading into said furnace and connecting with said aperture in the bottom 35 cover plate, whereby upon one of said pockets being filled through said aperture in the top cover plate, another pocket will deliver fuel into said chute for the furnace, means for delivering gas from the furnace into said filtering tank, said gas filtering tank being 40 adapted to be heated by the furnace, said tank being funnel-shaped and provided with a sieve at its enlarged upper end, a screen spaced above said sieve forming a scrubbing compartment above said sieve and a filtering chamber below the same, said compartment being filled with scrubbing material such as wood shavings and said chamber being 45 filled with a liquid forming the filtering material, and a pipe leading from the upper part of said water jacket into the ash pit of said furnace.

50 In testimony whereof I affix my signature.

FRANK E. MODLIN.
